UNITED STATES PATENT OFFICE.

CHARLES J. ABBE, OF ALDEN, MINNESOTA.

ADJUSTABLE MILK-CAN HOLDER AND PROTECTOR.

SPECIFICATION forming part of Letters Patent No. 639,645, dated December 19, 1899.

Application filed April 20, 1897. Serial No. 633,066. (No model.)

To all whom it may concern:

Be it known that I, CHARLES J. ABBE, a citizen of the United States, residing at Alden, in the county of Freeborn and State of Minnesota, have invented a new and useful Adjustable Milk-Can Holder and Milk-Can Protector, of which the following is a specification.

My invention relates to improvements in attachments for wagon-boxes and similar receptacles, by means of which a series of milk-cans may be held in said receptacles out of contact with each other and be easily inserted and removed; and to that end it consists in the features of construction hereinafter specifically described and claimed.

In the accompanying drawings, forming part of this specification, Figure 1 is a side elevation of a wagon-box fitted with my improved attachment and showing the side of the wagon-box partly broken away. Fig. 2 is a broken plan view of the wagon-box and my attachment. Fig. 3 is a rear end view partially broken away, and Fig. 4 is a longitudinal section.

In the drawings, A represents an ordinary wagon-box, to which is shown attached my improved device. The said device consists of a frame B, preferably of wood, provided with 30 downwardly-projecting arms 2, which are adapted to fit over the sides of the wagon-box and to be held in gripping position thereon by a connecting-screw 3, provided with screw-clamps 4.

5 represents the center piece, made of a pair of rods shaped to form openings for the cans and connected at one end by toggle-arms 6 and 7 with a transverse shaft 8, journaled in the end of the frame B, the toggle-joint being preferably provided with a spring 9. The opposite end of the center piece is similarly connected by toggle-arms 10 and 11 with a transverse shaft 12. The shafts 8 and 12 are turned to actuate said toggle-joints and raise 45 and lower the center piece through the medium of a lever 13, mounted upon the shaft 8 and working in connection with a toothed segment 14, said lever being connected by a rod 15 with a lever-arm 16, mounted upon the 50 end of the shaft 12. Projecting inward from the side bars of the frame B are triangles 17 to form spaces for the cans between the center piece and frame.

In use the device is secured to the wagon-box by the arms 2 and the milk-cans placed 55 in the openings formed by the center piece and the triangles 17. The center piece D is normally held in raised position by the interlocking of the lever 13 and segment 14. When it is desired to remove any of the milk-cans, 60 the lever 13 is released from the segment and turned, thus rotating the shafts 8 and 12 and actuating the toggle-joints to lower the center piece 5 to the bottom of the wagon-box. The lever being turned in the opposite direction 65 will return the center piece to raised position, in which position it is held by means of the spring-controlled dog 18, carried by the lever 13 and fitting in the notches 19 of the segment. 70

What I claim as my invention, and desire to secure by Letters Patent, is—

1. In combination with a wagon-box, an apparatus for holding a series of milk-cans therein consisting of a framework having 75 openings to receive the cans and means for vertically adjusting said frame.

2. In combination with a receptacle, means for holding a series of cans therein, consisting of a frame having openings to receive 80 said cans, and means for lowering said frame to the bottom of the receptacle to permit the removal of said cans.

3. In combination with a wagon-box, means for holding a series of cans therein consisting of a frame provided with a series of openings to receive the cans, means for lowering and raising said frame, and means for locking said frame in raised position. 85

4. A device of the class described, consisting of a frame, supported at its ends, means for vertically moving said frame upon its supports, and a lever for locking said frame in set position. 90

5. In combination with a wagon-box, means 95 for holding a series of milk-cans therein, and preventing the same rubbing together, consisting of a frame, a partition adjustably supported in said frame and normally separating said cans, a lever connected with both ends 100 of said partition and adapted to be actuated to lower the same.

CHARLES J. ABBE.
